UNITED STATES PATENT OFFICE.

CHARLES I. MILLAR, OF PROVIDENCE, RHODE ISLAND.

CAN-OPENER.

1,111,163.

Specification of Letters Patent. Patented Sept. 22, 1914.

Application filed June 5, 1913. Serial No. 771,842.

To all whom it may concern:

Be it known that I, CHARLES I. MILLAR, a citizen of the United States, and resident of the city of Providence, in the county of 5 Providence and State of Rhode Island, have invented certain new and useful Improvements in Can-Openers, of which the following is a specification.

This invention relates to can openers and 10 has for its object to provide in such a device a blade having a pointed end, and mounted to slide endwise in a suitable guiding body portion, an operating handle being pivoted in the body and having toothed engagement with said blade, the body being so 15 constructed as to provide, with the handle, suitable engaging means to be grasped by the hand of the operator to force the pointed end of the blade through the can whereby 20 the cutting edge of the blade is adapted to cut the can from the inner side outward when the handle is actuated.

With these and other objects in view, the invention consists of certain novel features 25 of construction, as will be more fully described and particularly pointed out in the appended claims.

Of the accompanying drawings: Figure 1— is a perspective view illustrating my 30 improved can opener with the handle in normal position. Fig. 2— is a sectional view of the frame illustrating in elevation the handle as being raised and in position to be grasped by the hand of the operator 35 to force the blade through the can. Fig. 3— is a perspective view of the body portion showing the side opposite to that shown in Fig. 1. Fig. 4— is a detail perspective view of the blade. Fig. 5— is a perspective view of a portion of the handle. Fig. 6— 40 is a section through the handle on line 6—6 of Fig. 5. Fig. 7— is a section through the blade on line 7—7 of Fig. 4.

Referring to the drawings 10 designates 45 the body portion which is preferably formed from sheet stock, the same being bent back substantially upon itself forming two spaced apart side walls 11 and 12. A portion of the wall 11 is turned inward as at 13 to 50 close the front of the body portion and serve as a front bearing for the knife blade shank. A short distance to the rear of this front wall the top and bottom edges of this wall 11 are notched as at 14 and 15 55 and the cut portions bent inwardly to serve the double purpose, first, as a rear bearing

for the knife blade shank, and second, to form stops to limit the stroke of the blade, lip 14 serving as the upward limit and 15 the limit of the downward stroke. The 60 forward extending loop 16 of this body portion performs a number of functions, first, it joins the side walls of the body portion; second, it serves as an extending bearing portion to rest upon the can and 65 act as a support for the stock as the blade is cutting the same, and third, it serves as a guard for the forwardly extending cutting edge of the blade. This body portion is also provided with laterally extending 70 ears 24 and 25, on opposite sides thereof, to serve as a rest and support the body while on the can and also to serve as a rest for the fingers of the operator while forcing the blade through the can to be opened. 75

The blade, best illustrated in Fig. 4, is preferably constructed of sheet steel and is provided with a shank 17 on the rear edge of which is formed a plurality of gear teeth 18, the lower end of the blade being 80 preferably made substantially in the form of a diamond-shape head having a sharp point 20 at its lower end adapted to pierce and enter the can and a forwardly extended cutting edge 19 adapted to cut the stock 85 as the head is drawn upward therethrough. This edge 19 is preferably beveled mostly on its right side, as illustrated in Fig. 7, which causes the blade to hug the left and cut the cover close to the edge of the can 90 in passing through the stock. In order to actuate this blade I have provided a handle 21 pivoted at 22 in the body portion. The forward end of this handle is provided with teeth 23 adapted to engage the 95 corresponding teeth 18 on the edge of the cutter shank. The handle is preferably formed of sheet stock and bent over into the shape illustrated in Fig. 6, thus being light in weight and adapted to nicely fit 100 the hand of the operator.

In assembling the parts and operating my improved device the body portion after having been stamped out of the sheet stock is bent up into shape and before the sides are 105 finally closed the blade and the actuating handle are mounted in their respective places between the walls thereof, said walls being spaced apart and said space being controlled by the inwardly turned fingers 14 and 15 and 110 a lower edge finger 26. The rivet is now inserted through the eye 27 of the handle

which serves a double purpose, first to form a pivot on which the handle oscillates and second, to prevent the side walls of the body portion from spreading.

5 In opening a can the handle is raised into position illustrated in Fig. 2 where it, together with the body portion, is grasped by the hand of the operator with his fingers resting upon the ears 24 and 25 he has a 10 good hold by which to force the pointed end and head of the blade through the can. The handle is now reciprocated the downward stroke of the same raising the blade so that the cutting edge 19 engages the inner side of 15 the can *a*, (a portion of which is illustrated in Fig. 2) and cuts it outward, the stock being supported between the walls of the forwardly extending portion 16 of the guard. At each stroke of the handle the device is 20 advanced by hand to rapidly and smoothly cut the can close to its outer edge all around its circumference. The upper tooth on the blade brings up against the stop 14 on the body portion and the lower tooth against 25 the stop 15, thereby limiting the stroke of the blade in both directions, the blade being set so that the forward point 27 of its cutting edge will not be raised to cut clear through the stock on the cutting stroke, 30 thereby insuring a guide to prevent the device from slipping out of the can upon each stroke of the handle.

It will be noted that by my improved construction a great leverage is obtained, giving 35 a very powerful cutting stroke and by beveling the knife on the angle, as illustrated in Fig. 7, the can is cut very smoothly and at its extreme edge all around its periphery.

40 I claim:

1. A can opener comprising a supporting frame, a blade mounted to be reciprocated therein, said blade having a piercing extension to enter the can and a laterally projecting outwardly turned cutting edge on said 45 extending portion to cut the can on its upward stroke, said blade having a toothed

shank, and an operating handle pivoted in said frame and having teeth engaging those of said shank whereby the oscillation of said handle causes said blade to reciprocate in said frame.

2. A can opener comprising a supporting frame, a blade mounted to be reciprocated therein and having a piercing and cutting extension adapted to enter the can, said blade having a laterally extending outwardly turned cutting edge adjacent said piercing extension to cut the can on its upward stroke, said blade having a toothed shank, and an operating handle pivoted in said frame and having teeth engaging those of said shank whereby the oscillation of said handle causes said blade to slide vertically in said frame, said body portion having laterally extended members adapted to support the hand of the operator in forcing the blade through the can.

3. A can opener comprising a hollow body portion constructed of sheet metal having two side walls formed by bending the metal substantially back upon itself leaving a space between, said body portion being adapted to be grasped by the hand of the operator and rest upon the face of the can, a knife blade mounted to be reciprocated between said walls, said blade having a piercing extension to enter the can and laterally projecting outwardly turned cutting edge on said projecting portion, said blade having teeth on one of its edges, and an operating handle pivotally mounted in said body and having teeth engaging those of said shank whereby the oscillating of said handle imparts a reciprocating movement to said blade to pass into and out of the can to cut the same.

In testimony whereof I affix my signature in presence of two witnesses.

CHARLES I. MILLAR.
